SELF-ACTUATED TRAFFIC SIGNAL SYSTEM

Benjamin M. Walpole, Providence, R. I.

Application December 9, 1930, Serial No. 501,084

19 Claims. (Cl. 177—337)

My invention relates to improvements in signalling devices and in fluid pressure actuating means therefor.

As the actuating means of my improved signalling device I employ a power means capable of actuating the signalling apparatus, a closed fluid conduit having a flexible actuatable portion and an actuating portion and connecting means actuated by said actuating portion to store up potential actuating energy in said power means on contact of an object on said flexible actuatable portion of said fluid conduit to become operable on release of said object contact to withdraw said connecting means from said power means to permit it to function to actuate the signalling device.

I have discovered that in employing a fluid conduit having a flexible actuatable portion like a hose that the sharp contact of an automobile or other vehicle thereover will transmit sufficient fluid pressure through said conduit to store up sufficient potential energy in the power means through the sharp rush of liquid or other fluid pressure through said conduit, and on release of said object from the flexible actuatable portion of said fluid conduit to permit said power means to function to actuate other means.

In my preferred embodiment, I employ this principle to actuate a traffic signalling device. The weight of the automobile sharply striking the actuatable portion of the fluid conduit will cause potential energy to be quickly stored up in the power means and on the release of the sharp rush of fluid pressure through said conduit the power means will be permitted to function.

In my preferred embodiment of fluid pressure for said conduit, I preferably employ a liquid pressure and where a liquid pressure is employed, I preferably also employ an overflow and supply reservoir connected to said conduit to keep a constant amount of liquid in said closed conduit. Thus if I employ a plurality of flexible traffic actuatable portions in said closed conduit as is desirable in street signalling systems and a traffic direction indicating device actuated by liquid pressure in said conduit, it is apparent that with a depression of one flexible portion by traffic the actuation of another flexible portion by traffic may permit said liquid pressure to actuate said traffic direction indicating device. This is a decided advantage not inherent in any former type of signalling apparatus so far as I am aware, for in former devices if one vehicle is on one pad in one traffic lane, it will prevent another vehicle approaching in the opposite direction in the

same traffic lane from actuating the corresponding opposite pad in the same lane to actuate the signal. Thus in my device if an automobile becomes stalled on the pad, the rest of the device can go right ahead and function whether it is stalled or not after the short period of time necessary to actuate the apparatus caused by the stoppage of the vehicle on said flexible actuatable portion. 5

If desired, my improved apparatus heretofore described may be used to actuate any kind of a signalling device whether it be a semaphore or lights controlled by the desired electrical circuit. If desired, it may be of the so-called reverting type particularly adapted for use in cross roads, 10 where a vehicle approaching at one cross road will bar traffic in the main highway for a predetermined time and then reopen it. This construction is employed where there is a main artery of traffic and a cross road seldom used, 15 and only necessitates the use of two flexible actuating portions on the cross road only.

In most instances, however, traffic on the approaching lane is more or less equal to that on the opposite lane and it is for this particular 25 type of traffic my invention particularly relates insofar as the signalling system itself is concerned. For this purpose, I provide two or more actuating pads on each lane on opposite sides of the intersection, thus broadly, right of way 30 indicating means for said lanes, a traffic actuatable control in one lane adapted on actuation thereof to move the indicating means to bar traffic in the other lane, a non-cyclic performance, and a traffic actuatable controller in the 35 other lane adapted in actuation thereof to move the indicating means to bar traffic in said first lane and it is to this type of apparatus that the broad improvements of my invention specifically relate. I specifically provide I believe for the 40 first time means effective on the actuation of one controller to prevent reactuation thereof until the opposite controller has been actuated, thus leaving the highway on which the controller has been actuated free for continuous passage of traffic 45 until a vehicle on the other highway actuates the signalling device to close said traffic. I also believe I am the first to provide in a traffic signalling device of this description, means to store up actuating energy in one controller while the 50 other controller is actuating, to permit said controller to actuate the right of way indicating means after the other controller has completed its action. This, therefore, provides a traffic signalling device which while still acting to open

up traffic in one lane, may after a vehicle approaching in the opposite lane has passed over its pad or actuating portion of the fluid conduit, store up sufficient energy to open up the traffic 5 in said lane after the traffic has passed through said other lane.

A further feature of my invention relates to the following combination for use in interfering traffic lanes; right of way indicating means in 10 said lanes, a traffic actuatable controller in one or both of said lanes, time controlled means actuated thereby to actuate said indicating means to bar traffic in the opposite lane for a predetermined time and in combination therewith 15 supplemental time controlled means effective on successive actuation of said controller to stop the actuation of said time controlled means during its operation for supplemental time controlled periods up to an adjustable maximum period. 20 This provides a very desirable type of construction, for in case there is a flow of traffic through one lane this supplemental time controlled means will be effective on successive actuation of the controller in said lane to keep that lane open 25 from a minimum predetermined time up to an adjustable maximum period by cutting out for a corresponding time controlled period, the functioning of the primary time controlled means. I, however, provide an adjustable maximum period 30 so as not to bar traffic in the opposite lane as it approaches beyond a reasonable time.

This type of device may be used for either type of a signalling device, namely, with a reverting device such as is hitherto described or with the preferred embodiment of my invention hitherto described in which there are actuating pads in each lane. In the reverting type of device the supplemental time controlled means will function to cut out the functioning of the primary controlled means just prior to its opening up traffic in the main line so as to prevent passage through the cross road for a predetermined adjustable length of time and when this has reached the desired maximum, the reverting primary time controlled means will automatically function to open up traffic in the main highway.

Where employed in the preferred type of my invention, however, where there are actuating pads in each lane, the supplemental time controlled means cooperates with said first time controlled means on successive actuation of said controller to extend the predetermined period in which said lane is open from a minimum up to an adjustable maximum and then permits after the termination of the adjustable maximum period, the passage of traffic through the other lane. The controller in said other lane is also preferably equipped with said supplemental time controlled means to keep said other lane open 55 from a minimum up to an adjustable maximum period for the same purpose until traffic in the opposite lane again opens it up.

Further objects of my invention relate to the specific mechanisms I employ for the purposes heretofore described and relate to the specific construction and timing of these various elements to accomplish the results desired.

A further object of my invention is to provide 70 a device which is relatively foolproof, which can be used at all times of the year, which is easy to operate, and which where a semaphore is employed is entirely independent of any outside electrical or other circuits or energy and which is entirely a self-acting, self-contained unit employ-

ing for its own use only the force of gravitation and no other type of power means than the energy furnished by the passing vehicles to start its primary actuation and its secondary reactuation where employed for longer time controlled 5 periods.

Further features of my invention relate to the specific construction of various component parts of my invention, it being observed that the specific construction of a so-called reverting type 10 of device is generally similar to the non-cyclic, the non-cyclic consisting of a duplication of certain parts of the reverting apparatus and the construction of the supplemental time controlled means except for the means for adjusting the time controlled feature thereof is generally similar to the specific construction of either type of primary time controlled actuating means, thus providing a structure which may be readily made at small cost as each part is substantially a 15 20 duplicate of others.

These and such other objects of my invention as may hereinafter appear are best understood from a description of the accompanying drawings which illustrate various embodiments 25 thereof.

In the drawings, Fig. 1 is a perspective view partially shown in section of two intersecting streets on which have been attached the non-cyclic or preferred embodiment of my invention 30 with my preferred type of right of way indicating means employing a visual semaphore and illuminated stop and go lights.

Fig. 2 is a diagrammatic plan view of such a crossing having the reverting embodiment of my 35 invention attached thereto on the cross roads.

Fig. 3 is a diagrammatic side elevation of the embodiment of my invention shown partly in section and partly in elevation showing the flexible actuatable portion of my improved closed 40 conduit about to be passed over by a vehicle to actuate the apparatus, showing various parts of my invention in full lines in inoperative position and in dotted lines in a maximum operating position.

Fig. 4 is a diagrammatic side elevation partially shown in section of the details of the semaphore features of my improved apparatus.

Fig. 5 is a cross-sectional view of the parts shown in Fig. 4.

Fig. 6 is a side elevation of the cam and means I preferably employ to actuate the semaphore feature of my invention.

Fig. 11 is a detailed side elevation of the specific supplemental time controlled means I employ with this embodiment.

Fig. 12 is an end elevation of the specific type of means I employ in Fig. 10 effective on the actuation of one controller to prevent reactuation 75

thereof until the opposite controller has been actuated.

Fig. 13 is a plan view of the apparatus shown in Fig. 10 and Fig. 14 is a plan view of the apparatus shown in Fig. 11.

Fig. 15 is a side elevation of the cyclic embodiment of my invention shown in Fig. 3 with a supplemental time controlled means preferably employed therewith.

Figure 16 is a view illustrating projections of the circular commutator contacts.

In the drawings, wherein like characters of reference indicate like parts throughout, 20 and 22 indicate two intersecting streets, intersecting as at 24. In Fig. 2 said streets comprise the main highway 20' and the cross road 22'.

In all the figures plain reference characters refer generically to similar parts in different units but where the reference characters are given subscripts of *a* or *b* or are primed, they refer to a particular street or unit.

As stated, my invention includes not only improvements in signalling systems but improvements in fluid pressure actuating means therefor. I believe I have provided a novel type of fluid actuating means which may be used preferably in connection with a signalling system for signalling traffic at cross roads and which may if desired be employed for other purposes. In my preferred traffic signalling system, I employ right of way indicating means 26 for said lanes 20 and 22. Said means may include both a semaphore 28 and an electric lighting circuit 30 and may include a central silent policeman shown at the center of said intersecting streets or may consist if desired of separate signals at each corner as is well known in the art today.

As stated hitherto, my improved traffic signalling device may consist of a so-called reverting type of traffic signalling device known in the art which is particularly adapted for use as shown in Fig. 2 where there is a main highway 20' intersected by a cross road 22'. In such a case I employ a traffic actuatable controller in one of said lanes preferably two controllers in the cross road one on each side of the intersection 24 and time controlled means actuated thereby to actuate the indicating means to bar traffic in the opposite lane for a predetermined time. Where the reverting embodiment of my invention is employed said time controlled means also functions after barring traffic for a predetermined time in the main highway 20' to again open up the main highway 20' for the passage of the usual traffic therethrough.

In the preferred embodiment of my invention, however, as illustrated in Figures 9 and 10 and also shown in Fig. 1, traffic actuatable controllers including also time controlled means may function to close one lane such as the lane 22 on actuation thereof by traffic in the other lane 20 and then on actuation thereof by traffic in said lane 22 to move the indicating means to bar traffic in said other lane 20 and it is to this specific non-cyclic type of signalling device which is particularly adapted for use in crowded city streets or any place where the traffic in each lane is substantially equal to which my invention particularly relates. This type of structure is also particularly desirable where the traffic on one street varies at different times of the day relative to traffic in the other street.

As stated, I preferably also employ supplemental time controlled means 32 effective on successive actuation of a controller to stop the actu-

ation of said primary time controlled means 34 during its operation for supplemental time controlled periods up to an adjustable predetermined maximum.

The basic features of the specific type of apparatus and specific type of fluid pressure actuated control therefor I preferably employ are generically common to all embodiments whether it be the reverting embodiment shown in Fig. 3 or the non-cyclic embodiment shown in Fig. 10 or the specific details of the supplemental time controlled means shown in Fig. 11. Each of these primary time controlled means 34 and secondary time controlled means 32 includes in combination a movable member 48, power means 38 to actuate said movable member in one direction through the member 36 a closed fluid conduit 40 having a flexible actuatable portion or pad 42 and an actuating portion specifically an upwardly forced diaphragm 44 actuated on increase of fluid pressure in said conduit due to the compression of the flexible actuatable portion 42 and connecting means 46 actuated by said actuating portion 44 to store up potential actuating energy in said power means 38 on contact of an object on said flexible actuatable portion 42 of said fluid conduit and operable on release of said object contact to withdraw said connecting means 46 from said power means 38 to permit it to function to move said movable member 36. In each of my embodiments shown the movable member 36 indirectly actuates the signalling mechanism in a manner to be hereinafter described.

In each of my embodiments shown, the flexible actuating portion 42 of the fluid conduit comprises the pads 42 located in the intersecting streets specifically as shown in Fig. 1 the pads 42^a and 42^{a'} located on opposite sides of the intersection 24 in the street 22 and the pads 42^b and 42^{b'} located in the street 20 where the non-cyclic embodiment of my invention is employed. Where the reverting embodiment of my invention is employed as illustrated in Figs. 2 and 3 the pads 42^b and 42^{b'} are omitted in the main highway 20.

Each of the primary and secondary time controlled means 34 and 32 includes a movable member 48, in my preferred embodiment a main gear 48 is rigidly secured to the shaft 50, a second movable member capable of reverse movements such as the pulley 36 in the embodiment shown in Fig. 3 or the pulleys 36^a and 36^b shown in Fig. 13 or the pulley 36' shown in Fig. 11 of the secondary time-controlled apparatus. I employ means connecting said movable members 36 and gear 48 to move together in one direction only. In all of the embodiments shown said means comprises the ratchet 52 fast to the shaft 50 and the pawl 54 pivotally mounted on the side wall of the pulley 36 loosely mounted on said shaft 50 to actuate said ratchet to rotate said gear 48 when said pulley 36 is moved in one direction.

I also preferably employ any suitable type of means attached to said second movable member 48 to make it move at uniform speed so that it may move over a predetermined time controlled interval. In my preferred embodiment I employ for this purpose a resisting fan 58 including suitable blades in mesh with said gear 48 although any other type of means for this purpose may be employed. I also employ power means 38 to impart motion in one direction only to said second movable member 36. As shown in my different embodiments any suitable type of power means may be employed, such as the spring 38' as shown

in Fig. 11 or the weights 38 shown in Figs. 3 and 10 suitably flexibly connected to the pulley 36 by means of a flexible cord 60.

In the preferred construction of my invention, I employ means to store up potential energy in said movable member 36 against the action of said power means 38. Said means includes the closed fluid conduit 40 having a flexible actuatable portion 42 and the actuating portion or diaphragm 44 and connecting means actuated by said actuating portion 44 to store up potential actuating energy in said power means on contact of an object on said flexible actuatable portion 42 of said fluid conduit 40 and operable on release of said object contact to withdraw pressure from said power means 38 to permit it to function to move said movable member or pulley 36.

In my preferred embodiment said connecting means is preferably constructed as follows: I employ an upper lever 62 pivotally mounted as at 64 on the frame 66. I also employ means such as a spring 68 connecting said lever 62 and frame 66 to normally urge said lever to lowered position. I provide a lower lever 70 also pivotally mounted on said frame 66 as at 72 and I provide a link 74 connecting upper lever 62 and lower lever 70 having a lost motion connection 76 to permit said upper lever to raise said lower lever and to move to lowered position regardless of the position of said lower lever 70. I also provide an arm 78 connecting said lower lever 70 to said pulley 36 to rotate said pulley 36 against the action of said power means 38 on raising of said upper lever 62 to store up potential energy in said power means 38.

I also provide latch means for said upper lever controlled by the position of said pulley to latch said upper lever in lower position against further actuation by said fluid conduit and releasable by said pulley 36 for a further actuation when said power means 38 has returned said pulley 36 to its initial normal position. In my preferred embodiment said latch is preferably constructed as follows. The latch 80 is pivotally mounted on said frame 66 as at 82. Said latch 80 has the upwardly projecting latch arm 84 having a notch 86 therein adapted to overlap the end of the upper lever 62. I also provide means such as a spring 87 attached to said frame 66 and latch 80 to normally raise said latch notch 86 to a position over the end of said lever 62. Said latch 80 is also provided with the outwardly projecting work arm 88 adapted to be abutted by the pin 90 projecting laterally from the side wall of the pulley 36. Fig. 3 illustrates the operation of said latch means, as said pulley 36 is raised so that the pin 90 is free of the work arm 88 of said lever, the spring 87 will automatically operate to pull the notch 86 of the latch 80 over around said lever 62 to retain it in lowered position so that repeated actuation of the flexible actuating portion 42 of the closed fluid conduit 40 will not be operative to raise said upper lever 62 to reactivate said apparatus. As the pulley 36 is returned to its normal initial position by means of the power means 38, it is obvious that the pin 90 will strike the work arm 88 to lower the notch 86 away from said upper lever 62 to permit it to be raised up on another actuation of the actuating portion 42 of said fluid conduit. This may take place after the pulley 36 has fully or partially returned to its normal position. In the reverting embodiment shown in Fig. 3, this takes place when the lower lever 70 has only partially returned to its lower position to permit a reactuation of the device to

prevent any vehicle from becoming stuck in the dead space between the pad and the intersection.

The operation of the features of my invention heretofore described is common to the embodiments shown in Figures 3, 9, 10 and 11. When a passing vehicle actuates the pad 42, it causes the actuating portion or diaphragm 44 of said closed conduit 40 to throw the upper lever 62 upwards against the pressure of the spring 68. The link 74 will then raise the lower lever 70 to the upper position shown in dotted lines in Fig. 3 simultaneously raising the arm 78 and throwing the second movable member or pulley 36 from the position shown in full lines to the position shown in dotted line in Fig. 3 against the pressure of said power means 38, the pawl 54 during this operation merely sliding over the teeth on the ratchet 52. Due to the lost motion connection 76 and the pressure of the spring 68, the upper lever 62 will be immediately returned to its lower position and the spring 87 will force the latch means 80 to retain said upper lever 62 in lowered position until later released by said latch means 80 in the manner heretofore described. It is then obvious that repeated actuation of the flexible portion 42 of the fluid conduit will not raise the upper lever 62, so that the rest of the apparatus will continue to function in its usual manner. When the lower lever 70 and arm 72 are raised to their maximum position it is obvious that the pulley 36 will be moved forward to its maximum operative position and that the pressure caused by the upward movement of the lever 62 caused by fluid pressure in the conduit 40 will be released and the pulley will be temporarily free. The power means, however, will then function to immediately act on the pulley to move it back to its original position and the pawl 54 engaging in the teeth 52 will then automatically revolve the gear 48 forward, the fan 58 acting as a brake on the power means 38 and gear 48 to cause it to move at a substantially uniform speed forward. The power means 38 will continue to revolve the pulley 36 to its initial position and the pin 90 abutting the arm 88 of the latch 80 will function to release the notch 86 from over the upper lever 62 in the manner heretofore explained to release said upper lever for reactuation as said pulley 36 nears its initial position.

Such features and operation of my invention as described are common to the reverting type of apparatus shown in Fig. 3, the non-cyclic shown in Fig. 10 and the secondary time controlled means shown in Fig. 11 and form in themselves a desirable subcombination for any use.

In the reverting embodiment shown in Fig. 3, due to the specific gearing employed the gear 48 will function to open up traffic in the cross road 22 and to return it to the main road 20 after a pad has been actuated in the cross road. In the non-cyclic embodiment shown in Fig. 10 the device will function merely to bar the traffic in the opposite road from that in which the controller has been actuated and the type of control affected depends merely upon the choice of gearing employed.

Whether the reverting embodiment shown in Fig. 3 or the non-cyclic embodiment shown in Fig. 10 be employed, the inherent parts of the signalling circuit and/or semaphore I preferably employ are substantially the same. The gear 48 in either embodiment drives the gear 92 fast to the shaft 94. The desired circular contacts 96, each of which include live portions 98 and in-

sulated portions 100 are also mounted on said shaft 94.

In the embodiments shown, I have shown three such circular contacts 96; one 96^a leading to the 5 green lights 102^b on the cross road 22 and the red lights 104^a on the main street 20. The second circular contact 96^b goes to the yellow lights 108^a on the main street 20 and 108^b on the cross road 22. The circular contact 96^c goes to the 10 green lights 102^a on the main street 20 and the red lights 104^b on the cross road 22. The contacts 96^a and 96^c are so spaced as not to overlap each other but to leave oversupply insulated portions to enable a function of the yellow lights by 15 the action of the contact 96^b intermediate each reversal thereof and the insulated portions 100 of the contact 96^c are substantially opposite the live portions 98 of the contact 96^a on the shaft.

In the reverting embodiment of my invention 20 upon an actuation of lever 70^a the gear 48 is stored with energy from the weight 38^a to close the commutator 96 to complete one revolution. While the drum 36 moves from actuated to rest position the result is that the green "go" light 25 will switch from the main highway 20 to the cross-road 22 and go back again to the main highway 20 a predetermined time after the vehicle has passed.

In the preferred embodiment of my invention 30 shown in Fig. 10, where each individual pad merely functions to bar traffic in the opposite lane, it is obvious that the contacts are so spaced or the movement of the gear so controlled as to not reopen traffic in the main highway again 35 after it has been opened up in the cross road and this matter of making the device cyclic or non-reverting is merely a matter of choice and can be accomplished by the changing of the gear 92 or the amount that the main gear 48 is moved on 40 each actuation by the traffic controllers 42. It is obvious that the circuit hitherto described connecting the various lights to the various circular contacts are controlled by the contact arms 112 suitably urged against the circular contacts 96 45 by the springs 114.

Where a semaphore is employed as shown in Figs. 3-7, I employ the semaphore cam 116. The semaphore 28 is adapted to be actuated by an oscillating movement. For this purpose the 50 semaphore 28 may be mounted inside the silent policeman 26 to normally show "go" on street 20 and "stop" on street 22 and to show alternately "go" and "stop" signals thereon. The pawl 118 is normally urged against the surface of said 55 semaphore cam 116 by the spring 120 and said pawl 116 is so connected with the semaphore 28 as shown in the drawings that as said pawl 118 is raised in the high and low substantially semi-circular portions of said cam 116 that said semaphore will be oscillated back and forth between the two streets 20 and 22, in the reverting embodiment, the semaphore being returned to the "go" position on the main street 20.

As stated, the various pads 42 form part of 60 the closed fluid conduit system namely, the flexible traffic actuated portion thereof. I provide means to actuate other mechanism actuated by the fluid pressure in said conduit on contact of traffic with said flexible portion and by using 65 fluid pressure, it is obvious that any flexible traffic portion may function to actuate said other mechanism, namely, the signalling apparatus shown despite the depression of another portion by traffic. This feature is very desirable in case 70 an automobile gets stalled or a child happens to

stand on one of the actuating pads. In the preferred type of liquid actuating pressure I preferably employ to insure this feature, I preferably provide an overflow and supply reservoir 122 to which liquid from said fluid conduit may suitably overflow or be supplied through the orifices 124 therein. It is thus obvious that if there is pressure on one pad the fluid may leak out from the fluid orifices 124 to raise the liquid level 126 in said reservoir 122 leaving the amount of liquid in the closed conduit for actuating purposes by another pad or controller 42 just the same as formerly and it is obvious that when pressure is removed from said pad that liquid may again flow from the reservoir 122 into the closed conduit 40 keeping a constant supply of liquid therein for actuating the signalling device or other mechanism.

In order to make my device substantially fool-proof I also may provide in my fluid conduit 40 a safety valve 128 to remove liquid or pressure from said closed system in case there is any excessive pressure on any or all of the pads 42 such as might be caused by a steam roller passing over them. I may employ any suitable type of actuating liquid but I preferably employ water and if desired to provide a non-freezing solution in the winter-time, denatured alcohol may be added. It is apparent, however, that other types of liquids or fluids may be used such as glycerine, oil, etc.

So much of my apparatus heretofore described namely the vehicle actuated controller is common to a cyclic or non-reverting and to the reverting and the secondary time controlled features of my invention. The apparatus shown in Fig. 3, and 30 which has already been described, is sufficient, per se, for the reverting system. The pads are provided only in cross street 22' (Fig. 2) and the signal controlling mechanism 92 or 116 and associated parts arranged to normally display the "go" 35 signal to the main highway 20'. A vehicle operating a pad in the cross street actuates the mechanism of Fig. 3 in the manner described to bar traffic in the main street and give the "go" signal to the cross street for a predetermined time. 40

As stated hitherto, particularly where there is a large amount of substantial equal or varying traffic in the different roads 20 and 22, it is desirable to provide controllers 42 in both the main highway 20 such as 42^b and 42^{b'} and in the cross 45 road 22 such as 42^a and 42^{a'} to move the indicating means to bar traffic in said opposite respective lanes 20 and 22. For this purpose I thus as shown in Fig. 1 provide the pads 42 and 42^{a'} on each side of the cross road 22 and the pads 42^b and 42^{b'} on each side of the main highway 20 and I provide separate time controlled mechanism for said respective pads and controllers on the roads 20 and 22 respectively actuated 50 and it is to this specific embodiment of my invention that my invention specifically relates. I provide in combination with said controllers in each highway to bar traffic in the opposite lanes, means effective on the actuation of one controller in one highway to prevent the reactivation thereof until the opposite controller in the opposite highway has been actuated. This therefore keeps the highway which has just been freed clear for the continuance of the passage of traffic thereover until traffic coming down the opposite highway functions to open up traffic in that highway. This results in the saving of 55 much wear on the apparatus and also where the specific type of continuously revolving right of way indicating means for said lanes is employed 60

adapted on each actuation thereof to transfer traffic right of way into said lane, to keep the traffic open in said lane until the opposite controller has been actuated. I also provide specifically in this combination means to store up actuating energy in one controller or in its respective time controlled portion while the other controller or respective time controlled means is actuating to permit said controller to actuate the 10 right of way indicating means after the other controller has completed its action. This means of storing up energy in itself to cause an actual transfer of the right of way indicating means by the passage of cars passing over said controller 15 alone, I believe is novel in non-cyclic signalling devices of this description.

I will now describe the specific embodiment of my invention shown in Fig. 10 which is preferably so constructed as to have these two novel 20 features heretofore described. The device shown in Fig. 10 employs a duplication of most of the elements shown in the device shown in Fig. 3. The common elements include the frame 66, the shaft 50 mounted transversely of said frame, the 25 main gear 48 rigidly mounted on said shaft adapted to have intermittent substantially equal forward movement, the resistance fan 58 in mesh with said gear 48 and the signalling device actuated by said gear on each respective forward 30 movement thereof. However, as in this device we have a supplemental set of pads 42^a and 42^b, or controllers located in the main highway 20 it is necessary to provide substantially duplicate parts of the time controlled mechanism adapted 35 to be actuated alternately by said respective controllers 42^a and 42^{a'} in the cross road 22 and the controllers 42^b and 42^{b'} in the cross road 20. The actuators for said main gear 48 independently controlled by traffic near the intersecting streets 40 20 and 22 include the controllers 42^a and 42^{a'} in the cross road 22 and the controllers 42^b and 42^{b'} in the main highway 20. I provide the two ratchets 52^a and 52^b mounted on each end of said shaft 50, the two pulleys 36^a and 36^b adapted to 45 be actuated by the independent controllers 42^a and 42^b and loosely mounted on each side of said shaft, the two pawls 54^a and 54^b each respectively mounted on the side walls of each pulley 36^a and 36^b to actuate said respective ratchets 52^a and 50 52^b when their respective pulleys 36^a and 36^b are moved in one direction, respective duplicate power means 38^a and 38^b to actuate their pulleys 36^a and 36^b in said direction, two upper levers 62^a and 62^b and springs 68^a and 68^b to urge each 55 respective lever to lowered position, two lower levers 70^a and 70^b also pivotally mounted on said frame, two links 74^a and 74^b connecting said upper levers 62^a and 62^b and lower levers 70^a and 70^b each respectively having a lost motion connection 60 76^a and 76^b to permit said upper levers 62^a and 62^b to raise their lower levers 70^a and 70^b and to move to lowered position regardless of the position of said respective lower levers 70^a and 70^b, two arms 78^a and 78^b respectively connecting said 65 lower levers 70^a and 70^b and pulleys 36^a and 36^b to rotate the respective pulleys against the action of the respective power means 38^a and 38^b on raising of said upper lever 62^a or 62^b to store up potential energy in said respective power 70 means 38^a or 38^b, two closed fluid conduits 40^a and 40^b of the manner hitherto described leading respectively to the controllers 42^a and 42^b and respective latch means 80^a and 80^b for the respective upper levers 62^a and 62^b.

75 As such features as just described are com-

mon in the embodiments shown in Fig. 3 and Fig. 10, only duplicate sets of the respective actuating means are provided for each respective controller 42^a or 42^b to respectively rotate the main gear 48 in desired amounts to switch the traffic from the road 20 to the road 22 on actuation of the respective controller 42^a or 42^b to respectively rotate the main gear 48 in desired amounts to switch the traffic from the road 20 to the road 22 on actuation of the respective controller 42^a or 42^b in the opposite highway and in this device the main gear is moved forward a certain amount and the contacts 96^a and 96^b are so spaced as to only permit a non-cyclic switching of the signals from one road to the other.

As stated hitherto, however, I provide in combination with the improved double type of non-cyclic signalling device I preferably employ, means effective on the actuation of one controller to prevent the reactivation thereof to keep 20 traffic in said lane open until the opposite controller has been actuated. In the preferred embodiment, (Fig. 12) shown said means comprises a spring actuated cross shaped lever 130 pivotally mounted on said frame 66 so as to have 25 the lower depending end 132 thereof pivot first over the upper lever 62^a and then up over the upper lever 62^b. The lower projecting end 132 of said lever is centrally notched as at 134 for a purpose to be described. The spring 135 is 30 connected to the frame 66 and to the upper projecting end 136 of said cross shaped lever to tend to prevent its pivoting. Said lever 132 is also provided with the sidewardly projecting cross arms 138^a and 138^b. The operation of this device is as follows: In the position shown in Fig. 12 the controller pad 42^b has just functioned to lift up the lever 62^b to close traffic in the side road 22. When a vehicle passes over a controller 42^a in said side road 22 it is obvious that it will 35 raise up the upper lever 62^a until it abuts the cross arm 138^a of said crossed shaped lever, thereby causing the downwardly projecting arm 132 to slide off of the opposite upper lever 62^b and the upper projecting portion 136 to pass 40 over the center and the downwardly projecting portion 132 to pass over the lever 62^a which has already by this time been lowered to its lower position. The spring 135 will then function to retain the downwardly projecting portion 132 over 45 the arm 62^a so that any number of reactivations of the controller 42^a will not permit the upper respective lever 62^a to be raised but the lever 62^b will be free to be raised on depression by another vehicle of the controller 42^b on the highway 20. 50

The means I provide to store up actuating energy in one controller 42^a, while the other controller is actuating, to permit the first controller 42^a or vice versa to actuate the right of way indicating means 26 after the other controller has 55 completed its action will now be explained. I provide circular locking plates 140^a and 140^b attached to each respective pulley 36^a and 36^b having single respective notches 142^a and 142^b in the peripheries thereof. I provide cams 144^a and 144^b rigidly mounted on the shaft 50 each having alternately raised and lowered arcs 146^a and 146^b and 148^a and 148^b respectively, each raised and lowered arc being approximately the distance of the pulley movement and the raised arcs 146^a and 146^b respectively on the cam 144^a being mounted on said shaft 50 so as to be complementary to the lowered arcs 148^b on said opposite cam 144^b. I provide pawl means 150^a and 150^b normally urged towards said cams 144^a and 75

144^b by the springs 152^a and 152^b, each having an arm 154^a and 154^b respectively adapted to contact the lowered arcs 146^b and 148^b of said cams 144^a and 144^b respectively to permit the pawl 5 proper portion 150^a and 150^b thereof to engage said respective notches 142^a and 142^b in said locking plates 140^a and 140^b to retain the respective pulley in raised position to store up actuating energy therein while said main gear 48 is being actuated 10 by the opposite actuator and operative at the release of the movement of said opposite actuator to release its respective pulley 36^a or 36^b for its supplemental action of said gear 48. It is thus apparent that while the opposite side of said 15 actuating device is being actuated to bar traffic on the opposite street for a predetermined length of time that a vehicle passing over an actuator on the opposite street may store up energy on its respective side to actuate the device to change 20 the signal to open up traffic in said street while the other actuator is still actuating, the cams 144^a and 144^b being arranged in the alternate manner heretofore described for this purpose. It is apparent that when the projecting portion 25 154 is raised up on to the raised portions 146 of said cam that it will free the pawl 132 from its respective notch 134 to then permit its respective power means to actuate the gear 48 to open up traffic in its respective lane. 30 A further feature of my invention relates to supplemental time controlled means effective on successive actuation of a controller to stop the actuation of said primary time controlled means 34 at a period of its cycle for supplemental time 35 controlled periods up to an adjustable maximum namely, the adjustable period of functioning of the supplemental time controlled means 32. As also stated hitherto in my preferred embodiment, the inherent parts of the supplemental time controlled means are respectively similar to the inherent parts of the primary time controlled means, the respective parts being designated by reference characters in Fig. 11 with prime numerals as heretofore described in unprimed time 40 controlled means. The supplemental time controlled means may be used as shown in Fig. 9 in association with the non-cyclic signalling device operated by controllers in each of the high-ways or as shown in Fig. 15 in association with the 45 50 cyclic type of controller shown in Fig. 3, which includes supplemental time controlled means and may be specifically modified for this purpose. Said supplemental time controlled means preferably functions in combination with the primary time controlled means to cut out the functioning of the primary time controlled means and functions itself for a period of time which may be extended by the successive actuation of said controlled means to extend said period of cutting 55 60 out the functioning of the primary time controlled means up to an adjustable maximum. In the improved combination in which this device is employed I provide the usual right of way indicating means 26 in the intersection, a traffic actuating controller 42 in one of the lanes, primary time controlled means 34 actuated thereby to actuate said indicating means 26 to bar traffic in said opposite lane for a predetermined time and supplemental time controlled means effective on 65 70 the successive actuations of said controller to stop the actuation of said time controlled means at a period of its cycle for supplemental time controlled periods up to an adjustable maximum period. 75 Said supplemental time controlled means is

substantially similar in construction except for the adjustable time controlled feature, to the primary time controlled actuating means 34 shown in Figs. 3 and 10 and includes the frame 66', a shaft 50' mounted transversely of said frame 66', a main gear 48' rigidly mounted on said shaft 50', a ratchet 52' rigidly mounted on said shaft 50', a resistance fan 58' in mesh with said gear 48', a pulley 36' loosely mounted on said shaft 50', a pawl 54' mounted on the side wall of said pulley 36' to actuate said ratchet when said pulley is moved in one direction, power means 38' to actuate said pulley in said direction, an upper lever 62' pivotally mounted on said frame 66', means 68' to normally urge said lever to lowered position, the lower lever 70', also pivotally mounted on said frame, the link 74' connecting said levers 62' and 70' having the lost motion connection 76' to permit said upper lever to raise said lower lever and to move to lowered position regardless of the position of said lower lever, an arm 78' connecting said lower lever 70' to said pulley 36' to rotate said pulley 36' against the action of said power means 38' on raising the said upward lever 62' to store up potential energy in said power means 38', the usual closed fluid conduit 40' and latch means 80' for said upper lever 62' heretofore described. The closed conduit 40' is attached to the closed conduit 40 as shown in Figures 9 and 15 and thus when the upper lever 62 30 of the primary time controlled means is locked the upper lever 62' of the supplemental time controlled means may be actuated on each actuation of the pad or flexible portion 42. 35 The gear 48', however does not actuate of itself the signalling device, but the position of the lower lever 70' controls a locking device for cutting out the functioning of the primary time controlled device 34 on the motor means. In order that the time of functioning of the secondary 40 time controlled means 32 be adjustably varied, I specifically provide the following apparatus for this purpose. I provide a ratchet 156 pivotally mounted on said upper frame 66' having a permanent stop 158 and an adjustable stop 160, said 45 adjustable stop being adjustable in holes 162 spaced apart substantially the distance of the ratchet teeth. I provide means such as the spring 164 to urge the permanent stop of said ratchet against a portion of said frame 66'. I 50 provide an actuating pawl 166 for said ratchet 156 pivotally mounted so as to depend at 168 from said upper lever 62' and normally urged by the medium of the spring 170 against said ratchet 156 when said upper lever is successively raised 55 to upward position by successive actuation of said controller 42 and adapted to rotate said ratchet 156 one tooth when said upper lever 62' is raised to its upper position and provided with the lateral projection 172 adapted to abut the pin 174 60 on said frame to release said actuating pawl 166 from said ratchet 156 after said lever is moved to lowered position. I also provide a releasing and retaining pawl for said ratchet, namely the pawl 178 pivotally mounted as at 180 on said frame and normally urged by the spring 182 to engage said ratchet 156 and having an arm 184 projecting upwardly therefrom adapted to be abutted by said lower lever 70' in lowered position 65 to release said ratchet, said releasing pawl being 70 adapted to engage successive teeth of said ratchet to increase the time controlled period up to a maximum limited by the position of said adjustable stop 160 so said actuating pawl will become engaged with a tooth on the ratchet 156, thereby 75

no longer permitting the upper lever 62' to be raised to successively raise the lower lever 70' and it is obvious that when the lower lever 70' is lowered to its lowermost position the arm 184 5 will force the releasing and retaining pawl away from the ratchet teeth 156 so that the spring 164 will pivot the ratchet to zero position and thereby free the device.

When the supplemental time controlled means 10 32 is employed in the reverting embodiment as shown in Fig. 15, it is obvious that only one of them will be required. When, however, my improved supplemental time controlled means is employed in the embodiment shown in Figs. 9 15 and 10 it is obvious that parts of two will be needed, namely, individual parts for each respective actuating portion 34 of the primary controlled means adapted to be independently actuated by the pads 42^a and 42^b. In either case, 20 however, the following locking means and releasing means is similar.

I provide means effective on actuation of said supplemental time controlled means 32 when said primary time controlled means 34 has been 25 locked to stop the actuation of said primary time controlled means during the actuation of said supplemental time controlled means. While any suitable means may be provided for this purpose, I preferably provide the link 186 projecting downwardly from the lower lever 70' of the supplemental time controlled means 32 preferably with the lost motion connection 188 at its lower end. Said lost motion connection functions on raising 30 up of said lower lever 70' to permit the spring 190 35 to urge the pawl 192 into a tooth of the main gear 48 to cut out the functioning of the primary time controlled means 34 when said lower lever 70' is raised to an upward position. When the lower lever 70' sinks to its lowermost position, it 40 is obvious that the link 186 will force the pawl 192 out of contact with the teeth on the gear 48 to free the primary time controlled means 34 for further action.

In order to permit the functioning of the secondary time controlled means 34, I provide means 45 actuated by said primary time controlled means to release said supplemental time controlled means 32 to be successively actuated by said controller at a time substantially near the end of the operation of said primary time controlled means. For this purpose said means comprises a pin or 50 set of pins 194 projecting laterally from said gear 48 adapted to abut an arm 196 normally urged downwardly by the spring 198 to release through a suitable system of linkage 200 a latch 202 which functions to lock the upper lever 62' of the supplemental time controlled means 32 in lowered 55 position. The secondary time controlled means is preferably so timed that it may be re-actuated by a second impulse substantially half way to lowered position of the pulley 36' and the lower lever 70' and it is thus apparent that such successive actuation of the secondary time controlled mechanism may take place in the manner heretofore described up to a predetermined maximum limited by means of the adjustable stop 160 in said adjusting ratchet 156. Where my improved non-cyclic apparatus is employed, it is apparent that there will have to be a suitable 60 duplication of certain features of the supplemental time control thereof, namely, duplicate secondary pressure connections 40^a and 40^b and actuated portions 48^a and 48^b thereof, duplicate upper levers 62^a and 62^b, links 74^a and 74^b 65 and duplicate latches 202^a and 202^b respectively

actuated by duplicate arms 196^a and 196^b respectively actuated by duplicate pins 194^a and 194^b for the respective sides of the primary time controlled actuating mechanism. A single secondary time controlled means in all other respects is 5 sufficient and is suitably connected to the opposite side of the primary time controlled means in the manner heretofore described. It is obvious that the secondary time controlled means will only be 10 released for functioning when one of the alternate primary controlled means is functioning by the respective pin 194^a or 194^b abutting its respective arm 196^a or 196^b to release its respective latch 202^a or 202^b for the functioning of the secondary time controlled means. 15

It is apparent that I have provided not only a novel type of traffic signalling device, but also specific novel types of fluid pressure actuated control therefor, which specific type of fluid pressure actuated means may be used in other connections than for signalling or if desired signalling for foot traffic as well as for vehicular traffic. It is also apparent that my improved type of fluid pressure actuating apparatus may be employed for actuating a counting clock or other 20 similar device as well as for the specific signalling purpose shown. 25

It is understood that my invention is not limited to the specific embodiments shown and that various deviations may be made therefrom without departing from the spirit and scope of the appended claims. 30

What I claim is:

1. In a traffic signalling apparatus, a frame, a shaft mounted transversely of said frame, a main gear rigidly mounted on said shaft, a ratchet rigidly mounted on said shaft, a resistance fan enmeshed with said gear, a signalling device controlled by said gear, a pulley loosely mounted on said shaft, a pawl mounted on a side wall of said pulley to actuate said ratchet when said pulley is moved in one direction, power means to actuate said pulley in said direction, an upper lever pivotally mounted on said frame, means to normally urge said lever to lowered position, a lower lever also pivotally mounted on said frame, a link connecting said levers having a lost motion connection to permit said upper lever to raise said lower lever and to move to lowered position regardless of the position of said lower lever, an arm connecting said lower lever and said pulley to rotate said pulley against the action of said power means on raising of said upper lever to store up potential energy in said power means, a closed fluid conduit having a flexible actuatable portion and an actuating portion connected to said upper lever adapted to raise said lever on contact of an object on said flexible actuatable portion of said fluid conduit to store up potential energy in said power means, and latch means for said upper lever controlled by the position of said pulley to latch said upper lever in lower position against further actuation by said fluid conduit and releasable by said pulley for a further actuation when said power means has returned said pulley substantially to its initial normal position. 55

2. In a traffic signalling apparatus, a main gear rigidly mounted on a shaft, a ratchet rigidly mounted on said shaft, a resistance fan enmeshed with said gear, a signalling device controlled by said gear, a pulley loosely mounted on said shaft, a pawl mounted on a side wall of said pulley to actuate said ratchet when said pulley is moved in one direction, power means to actuate said pulley in said direction, an upper lever pivotally 70

mounted on said frame, means to normally urge said lever to lowered position, a lower lever also pivotally mounted on said frame, a link connecting said levers having a lost motion connection 5 to permit said upper lever to raise said lower lever and to move to lowered position regardless of the position of said lower lever, an arm connecting said lower lever to said pulley to rotate said pulley against the action of said power 10 means on raising of said upper lever to store up potential energy in said power means, a closed fluid conduit having a flexible actuatable portion and an actuating portion connected to said upper lever adapted to raise said lever on contact of an object on said flexible actuatable portion of said fluid conduit to store up potential energy in said power means.

3. In a traffic signalling device, a frame, a shaft mounted transversely of said frame, a main gear rigidly mounted on said shaft to have intermittent equal forward movements, a resistance fan enmeshed with said gear, a signalling device actuated by said gear on each forward movement thereof, two actuators for said gear independently 25 controlled by traffic in intersecting streets, each including two actuating controllers in one street, a ratchet mounted on opposite sides of said shaft, a pulley loosely mounted on said shaft, a pawl mounted on a side wall of said pulley to actuate said ratchet when said pulley is moved in one direction, power means to actuate said pulley in said direction, an upper lever pivotally mounted on 30 said frame, means to normally urge said lever to lowered position, a lower lever also pivotally mounted on said frame, a link connecting said levers having a lost motion connection to permit said upper lever to raise said lower lever to move to lowered position regardless of the position of said lower lever, an arm connecting said lower lever to said pulley to rotate said pulley against the action of said power means on raising of said upper lever to store up potential energy in said power means, a closed fluid conduit having a flexible actuatable portion and an 35 actuating portion connected to said upper lever adapted to raise said lever on contact of an object on said flexible actuatable portion of said fluid conduit to store up potential energy in said power means, latch means for said upper lever controlled by the position of said pulley to latch said upper lever in lower position against further actuation by said fluid conduit and releasable by said pulley for a further actuation when said power means has returned said pulley to its initial normal position, a circular locking 40 plate attached to each pulley having a notch in the periphery thereof, a cam rigidly mounted on said shaft having alternately raised and lowered arcs, each raised and lowered arc being approximately the distance of the pulley movement, the 45 raised arcs on one cam being complementary to the lowered arcs on the opposite cam, pawl means normally urged towards said cam and notch having a portion adapted to contact the depression in said cam to permit said pawl to engage said notch to retain said pulley in raised position to store up actuating energy therein while said gear is being actuated by the opposite actuator and operative at the end of said movement to release said pulley 50 for a supplemental actuation of said gear and a tiltable locking device operative to lock one actuating lever after an actuation thereof until the opposite lever has been actuated.

4. A traffic signalling device for interfering 75 traffic lanes having in combination right of

way indicating means for said lanes, a traffic actuatable controller in one of said lanes, time controlled means actuated thereby to actuate said indicating means to bar traffic in the opposite lane for a predetermined time, supplemental time controlled means effective on successive actuation of said controller to stop the actuation of said time controlled means at a period of its cycle for supplemental time controlled periods up to an adjustable maximum period comprising 5 a frame, a shaft mounted transversely of said frame, a main gear rigidly mounted on said shaft, a ratchet rigidly mounted on said shaft, a resistance fan enmeshed with said gear, a signalling device controlled by said gear, a pulley 10 loosely mounted on said shaft, a pawl mounted on a side wall of said pulley to actuate said ratchet when said pulley is moved in one direction, power means to actuate said pulley in said direction, an upper lever pivotally mounted on 15 said frame, means to normally urge said lever to lowered position, a lower lever also pivotally mounted on said frame, a link connecting said levers having a lost motion connection to permit said upper lever to raise said lower lever to move to lowered position regardless of the position of said lower lever, an arm connecting said lower lever and said pulley to rotate said pulley against the action of said power means on raising of said upper lever to store up potential energy in said power means, a closed fluid conduit having a flexible actuatable portion and an actuating portion connected to said upper lever adapted to raise said lever on contact of an object on said flexible actuatable portion of said fluid conduit to store up potential energy in said power means, latch means for said upper lever controlled by the position of said pulley to latch said upper lever in lower position against further actuation by said fluid conduit and releasable by said pulley for a further actuation when said power means has returned said pulley substantially halfway to its initial normal position, a ratchet pivotally mounted on said frame having a permanent stop and an adjustable stop, said 20 adjustable stop being adjustable in holes spaced apart substantially the distance of the ratchet, means to urge said ratchet against said permanent stop, an actuating pawl pivotally mounted on said upper lever and normally urged against said ratchet when said upper lever is successively raised to upper position by successive actuation of said controller and adapted to rotate said ratchet one tooth as said upper lever is raised to its upper position and means to release said actuating pawl from said ratchet as said lever is moved to lower position, a releasing pawl pivoted on said frame to engage said ratchet having an arm adapted to be abutted by said lower lever in lower position to release said ratchet, said pawl being adapted to engage successive teeth of said ratchet to insure the time controlled period up to a maximum limited by the position of said adjustable stop as said actuating pawl rotates said ratchet and means actuated by said primary time controlled means to release said supplemental time controlled means to be successively actuated by said controller at a time substantially near the end of its cycle and means effective on an actuation of said supplemental time controlled means to stop actuation of said primary time controlled means during the actuation of said supplemental time controlled means.

5. In a traffic signalling system for intersecting lanes, a right of way indicating device, a 75

traffic actuated device in one lane capable of receiving energy from a unit of traffic actuating it and transmitting it, means actuated by and operating entirely from such energy to actuate said right of way indicating device to transfer the right of way to the lane of said actuated device for a predetermined time and then to re-transfer the right of way to another of said lanes, and a means also actuated by and operating entirely from such energy from repeated actuations of said device within a predetermined time to extend the time before re-transfer up to a predetermined maximum.

6. In a traffic signal device the combination 15 with a signal adapted to be disposed at the intersection of two thoroughfares, and having traffic directing means thereon adapted alternately to be displayed to permit traffic to proceed on one thoroughfare and to restrain traffic on the other 20 thoroughfare, of a vehicle operated device in one of said thoroughfares spaced from said signal capable of receiving energy from a unit of traffic actuating it and transferring it, means entirely operated by said supplied and transmitted 25 energy for setting the signal after each of said vehicles operates said first mentioned vehicle operated device to permit traffic to proceed on said thoroughfare, means for holding the signal so set for a determined period also entirely operated 30 by said supplied and transmitted energy until said vehicle has had time to pass said intersection, a vehicle operated device in the other thoroughfare also capable of receiving energy from a unit of traffic actuating it and transfer- 35 ring it, means entirely operated by said supplied and transmitted energy of said last mentioned vehicle operated device for setting the signal to permit traffic to proceed on said last mentioned thoroughfare, means entirely operated by 40 said supplied and transmitted energy of said first mentioned device when actuated by said vehicle or subsequent vehicles for preventing said signal being set by said last mentioned vehicle operated device for a certain period, and means 45 also entirely operated by said supplied and transmitted energy whereby the means actuated by said last mentioned vehicle operating device will change the signal as soon as said period is ended.

7. In a traffic signal device, the combination 50 with a signal adapted to be disposed at the intersection of two or more thoroughfares and having traffic directing means thereon adapted to be displayed alternately to direct traffic to proceed 55 on one thoroughfare and restraining traffic on another thoroughfare, a traffic operated device for one of said thoroughfares capable of receiving energy from a unit of traffic actuating it and transferring it, means entirely operated by said supplied and transmitted energy by operation of 60 said device for setting the signal to direct traffic to proceed on said thoroughfare, a traffic operated device on the other thoroughfare, also capable of receiving energy from a unit of traffic actuating it and transferring it, means entirely 65 operated by said supplied and transmitted energy by operation of said last mentioned device for setting the signal for traffic to proceed on said last mentioned thoroughfare, means actuated and 70 energy entirely supplied by operation of said first mentioned traffic operated device for so setting the signal and in a plurality of subsequent operations thereof while the signal is so set for preventing the signal being set by operation of said last mentioned traffic operated device for a cer-

tain definite period of time, and means also entirely operated by said supplied and transmitted energy, whereby said means operated by said second traffic operated device entirely operated by said supplied and transmitted energy by operation of said last mentioned traffic operated device will change the signal as soon as said period of time has lapsed to direct traffic to proceed on the thoroughfare in which said last mentioned traffic operated device is located.

8. A traffic signalling apparatus having, in combination, a visual signal approachable by traffic on each of a plurality of different lanes and having means operable to shift signal indication so as to transfer right of way between said lanes, a traffic actuatable controller capable of receiving energy from a unit of traffic actuating it and transmitting it to entirely supply the energy for operation of said means in one of said lanes and on the approach to said signal, said means including mechanism cooperable with said controller to control transfer of right of way and, by successive actuation of said controller within a predetermined interval by vehicles approaching the signal, to prolong the period of continuity of right of way in one lane beyond a predetermined minimum period but not beyond a predetermined maximum period before transfer from the latter lane.

9. A traffic signalling apparatus having, in combination, a visual signal approachable by traffic on each of a plurality of different lanes and having means operable to shift signal indication so as to transfer right of way between said lanes, a traffic actuatable controller in one of said lanes and on the approach to said signal capable of receiving energy from a unit of traffic actuating it and transmitting it to entirely supply the energy for said means, said means including mechanism cooperative by actuation of said controller by a vehicle approaching the signal, to cause such actuation of said signal as to transfer right of way back and forth between said lanes and a device operable, by successive actuation of said controller within a predetermined interval by vehicles approaching the signal, to prolong the period of continuity of right of way in the lane of the controller beyond a predetermined period before transfer from the lane of the controller.

10. In a traffic signal device, the combination, with a signal adapted to be disposed at the intersection of two or more thoroughfares and having constantly operative means for directing traffic to go on one thoroughfare and stop on the other, or vice versa, a vehicle operated device in one of said thoroughfares, capable of receiving energy from a unit of traffic actuating it and transmitting it to entirely supply the energy for operating said signal, to display a go sign on said thoroughfare and a stop sign on the other, means actuated and energy entirely supplied by said device for holding the signal so set for a determined period of time to permit said vehicle to cross said intersection, a vehicle operated device on the other thoroughfare, capable of receiving energy from a unit of traffic actuating it, and transferring it, means entirely operated by said supplied and transmitted energy by said latter device for setting said signal to display a go sign on said other thoroughfare and a stop sign on 60 said first mentioned thoroughfare, and means actuated and energy entirely supplied by said first mentioned device, when actuated by a plurality of subsequent vehicles for preventing said signal being set by said last mentioned means 65 70 75

for a definite period of time after each of said vehicles operates said first mentioned vehicle operated device, whereby said subsequent vehicles operating said first mentioned device will respectively have time to pass the intersection before the signal is changed.

11. The structure set forth in claim 10, and means also entirely operated by said supplied and transmitted energy, whereby said means actuated by said last mentioned vehicle operated device will set said signal so that the last said go sign changes at once to stop and the stop sign to go as soon as said period of time is ended.

12. A traffic signal device having in combination, a signal adapted to be disposed at the intersection of two or more thoroughfares and having constantly illuminated traffic directing means thereon including means for directing traffic to go on one thoroughfare and stop on the other thoroughfare, or vice versa, a traffic operated device for one of said thoroughfares capable of receiving energy from a unit of traffic actuating it and transferring it, means entirely operated by said supplied and transmitted energy by operation of said device for setting the signal to direct traffic to proceed on said thoroughfare, a traffic operated device on the other thoroughfare also capable of receiving energy from a unit of traffic actuating it and transmitting it, means entirely operated by said supplied and transmitted energy by operation of said last mentioned device for setting the signal for traffic to proceed on said last mentioned thoroughfare, means entirely operated by said supplied and transmitted energy by operation of said first mentioned traffic operated device in so setting the signal and in a plurality of subsequent operations thereof, while the signal is so set for preventing the signal being set by operation of said last mentioned traffic operated device for a certain definite period of time, and means also entirely operated by said supplied and transmitted energy whereby said means actuated by operation of said last mentioned traffic operated device will change the signal as soon as said period of time has elapsed to direct traffic to proceed on the thoroughfare in which said last mentioned traffic operated device is located.

13. A traffic signal device adapted to be disposed at the intersection of two or more thoroughfares having in combination, a signal having illuminating means, a circuit containing certain of said illuminating means for causing said signal to direct traffic to go on one thoroughfare and stop on another thoroughfare when said circuit is closed, a second circuit containing certain other of said illuminating means for causing said signal to direct traffic to stop on said first mentioned thoroughfare and go on the other when said second circuit is closed, means constantly operative to close one of said circuits and open the other, and vice versa, a traffic operated device in one of said thoroughfares capable of receiving energy from a unit of traffic actuating it and transferring it, means entirely operated by said supplied and transmitted energy by operation of said device for causing said last mentioned means to close said first circuit and open said second circuit, a traffic operated device in the other thoroughfare capable of receiving energy from a unit of traffic actuating it and transferring it, means entirely operated by said supplied and transmitted energy by operation of said last mentioned device for causing said first mentioned means to close said second circuit and open said first

circuit, means also entirely operated by said supplied and transmitted energy actuated by operation of said first mentioned traffic operated device in so closing said first circuit and in a plurality of subsequent operations thereof while said first circuit is still closed for preventing said first mentioned means from closing said second circuit for a definite period of time, and means also entirely operated by said supplied and transmitted energy whereby said means actuated by operation of said last mentioned traffic operated device will close said second circuit as soon as said period of time has elapsed, to direct traffic to proceed on said thoroughfare in which said last mentioned traffic operated device is located. 10

14. In a traffic signal apparatus for interfering lanes, right of way signalling means for normally displaying right of way to one of said lanes, a traffic actuated controller capable of receiving energy from a unit of traffic actuating it and transferring said energy, means controlled by and operating entirely from energy supplied by an actuation of said controller for a predetermined period of time to transfer said right of way to another of said lanes for a predetermined period of time not greater than first said period and then re-transferring said right of way back to the said one lane. 20

15. An apparatus defined in claim 14 wherein the last said means is operative by energy supplied by subsequent actuations of said controller during right of way to said other lane to extend said periods. 30

16. In a traffic signal apparatus for interfering lanes, right of way signalling means for normally displaying right of way to one of said lanes, a traffic actuated controller capable of receiving energy from a unit of traffic actuating it and transferring said energy, said controller being located in another of said lanes, means controlled by and operating entirely from energy supplied by an actuation of said controller for a predetermined period of time to transfer said right of way to said other lane for a portion of said period and then retransfer it back to said one lane for a 45 remaining portion of said period. 35

17. An apparatus defined in claim 16 wherein the last said means is operative by energy supplied by subsequent actuations of said controller during display of right of way to said other lane 50 to delay retransfer of right of way back to the first lane.

18. A traffic signalling system for intersecting lanes, a right of way indicating device, a traffic actuated device in one lane capable of receiving energy from a unit of traffic actuating it and transmitting it, means actuated by and operating entirely from such energy to actuate said right of way indicating device to display and maintain the right of way to the lane of said actuated device for a determined time, and then to permit transfer of the right of way to another of said lanes, and means also actuated by and operating entirely from such energy from repeated actuations of said device before said transfer to extend the time before said transfer up to a predetermined maximum. 55

19. An apparatus as defined in claim 18 including means associated therewith to hold the right of way in said other lane when transferred thereto for a definite period of time before further actuations on said device in said first lane can again retransfer the right of way to said first lane. 70
